UNITED STATES PATENT OFFICE.

GEORGE W. DEPEW, OF PEEKSKILL, NEW YORK, ASSIGNOR TO HORTON,
DEPEW & SONS, OF SAME PLACE.

IMPROVEMENT IN PLOWS.

Specification forming part of Letters Patent No. 31,761, dated March 19, 1861.

To all whom it may concern:

Be it known that I, GEORGE W. DEPEW, of Peekskill, in the county of Westchester and State of New York, have invented a new and useful Improvement in Plow-Clevises; and I do hereby declare that the following is a full, clear, and exact description of the same, reference being had to the annexed drawings, making a part of this specification, in which—

Figure 1 is a side view of a plow provided with my improvement; Fig. 2, a section of the same, taken in the line $x x$, Fig. 3; Fig. 3, a plan or top view of the same; Fig. 4, a section of the same, taken in the line $y y$, Fig. 2.

Similar letters of reference indicate corresponding parts in the several figures.

The object of this invention is to obtain a clevis that may be very readily adjusted on the end of the plow-beam, so that the plow may have more or less pitch to plow deep or shallow, as may be required, the clevis at the same time being attached or connected to the plow-beam in such a manner as to preclude the possibility of its casual detachment.

To enable those skilled in the art to fully understand and construct my invention, I will proceed to describe it.

A represents a plow-beam, which is of curved form and provided at its upper and lower edges with flanges $a a$, which project out from each side of the beam, so as to leave a groove or concave, b , at each side, as shown clearly in Fig. 4. The beam is of cast-iron, and its upper flange a terminates at the back part of the beam, as shown at c in Fig. 1.

The front end of the beam A is inclined, as shown clearly at a' in Figs. 1 and 2, and at each side of the beam, at its front part, there are notches e , which may be described as being in ledges f , which form the front ends of the grooves or concaves $b b$, and connect the front ends of the flanges $a a$. Three notches, e , are shown at each side of the beam A; but more or less may be used, as desired. The notches e at each side of the beam are in lines parallel with the inclined end a' of the beam, as shown clearly in Figs. 1 and 2. The beam with its flanges $a a$ and edges f are all cast in one piece.

B represents the clevis, which may be of cast-iron. This clevis is of flat form, and has three holes, $g g' g''$, in it at its front part, any of which may receive the draft-hook. (See

Fig. 3.) The holes $g g' g''$ are in a line about at right angles with the plow-beam. The back part of the clevis is provided with a square or rectangular recess, a'' , which forms two prongs or arms, $h h$, from the inner sides of which, and near their ends, pins $i i$ project at right angles, one from each arm. The space between the ends of the pins $i i$ is narrower than the flanges $a a$, and the clevis is fitted on the beam by placing it over the back part behind the upper flange, a , at c , and then shoving the clevis forward to the front end of the beam.

The flanges $a a$, it will be seen, prevent the casual detachment of the clevis from the beam, as the pins $i i$ project within the grooves b , as shown clearly in Fig. 4.

The pins $i i$ of the clevis may be fitted in any one of the notches e , according to the degree of pitch it is necessary to give the plow. If deep plowing is required, the pins i are adjusted in the upper notches, the pitch being decreased by adjusting the pins in the lower notches. The front edge of the recess a'' rests against the inclined front end, a' , of the beam A, and said end a' , in connection with the pins $i i$ and notches $e e$, retain the clevis in the desired position.

It will be seen from the above position that it is essential that the end a' of the beam and the notches e at each side of the beam be in parallel inclined lines or planes in order to effect the result described.

In order to give the plow land the draft-hook is adjusted in the extreme right-hand hole, g'' , a straight or direct draft being obtained by adjusting the draft-hook in the central hole, g' . A draft tendency from the land is obtained by adjusting the draft-hook in the hole g .

I do not claim broadly or separately a clevis provided with a series of holes or notches, for they have been previously used; but

I do claim as new and desire to secure by Letters Patent—

A clevis, B, provided with arms $h h$, which have pins $i i$ projecting therefrom, in connection with a plow-beam, A, having flanges $a a$ at its upper and lower edges, and provided with an inclined front end, a' , and notches $e e$, all arranged as and for the purpose set forth.

GEORGE W. DEPEW.
